BALL VALVE

Harrison J. Britton, Upper Montclair, N.J., assignor to
Hydromatics, Inc., a corporation of New Jersey

Filed July 16, 1962, Ser. No. 70,946

Term of patent 14 years

(Cl. D91—3)

FIG.1

FIG.2

FIG.3

FIG.4

FIG. 1 is a perspective view of a ball valve showing my new design;

FIG. 2 is a side elevation;

FIG. 3 is a bottom plan view; and

FIG. 4 is an end elevation.

The equally spaced parallel lines on the upper surface of the handle represent conventional grooves.

I claim:

The ornamental design for a ball valve, as shown and described.
